LEVEL INDICATOR FOR LIQUID MIXTURES

Mariano Verduzco, Mexico City, Mexico

Application October 5, 1939, Serial No. 298,045
In Mexico October 8, 1938

3 Claims. (Cl. 33—126.7)

This invention relates to a device for graduated the contents of a cylindrical container. It is a well recognized fact that mixtures of various liquids such as paint colors may only be made by properly proportioning the quantities of each of the paint colors and their components if a uniform color is to be obtained from the mixed paints.

One object of the present invention is to provide a novel device whereby such mixtures of liquids may be measured by a single operating device which may be correlated with the containers for such mixtures.

A second object of the device is to provide a construction wherein, independently of the height of the container, the proportionate mixtures may be made.

With the above and other objects in view, the invention consists in general of certain novel details of construction and combinations of parts hereinafter fully described, illustrated in the accompanying drawing, and particularly pointed out in the claims.

In the accompanying drawing, like characters of reference indicate like parts in the several views, and:

Fig. 1 is a schematic side view of one form of the invention irrespective of the container.

Fig. 2 is a view similar to Fig. 1 showing the measuring device at the bottom of the container.

Fig. 3 is a view similar to Fig. 1 showing the measuring device at the top of the container.

Fig. 4 is a view of a modified form of the device wherein a graduated segment is employed, the view showing the device at its lowest point of measurement.

Fig. 5 is a view similar to Fig. 1 but showing the device at its highest point of adjustment.

Fig. 6 is a view, partly in full lines and partly in dotted lines, showing the relative positions of the measuring devices in their highest and lowest points of adjustment.

Fig. 7 is a detail showing the liquid contacting end of a certain measuring device shown in connection herewith.

Fig. 8 is a further illustration of a form of this invention.

In the various forms of the invention there is provided a base 1 and from one end of this base there extends upwardly a post 2 which has its upper end curved to overhang the base 1. At 3 is a platform adapted to have a container 4 rest thereon and this platform is vertically slideable on the post 2, the platform being attached to a sleeve 3a through which a clamping screw 3b ex-

tends to engage the post 2 and thereby secure the platform 3 to any desired height, such height depending on the height of the container 4. It is to be observed that the post 2 is provided with graduations 10 which extend up to the point 11 at which the post starts to curve over the base 1 and the platform 3. At the upper end of the post 2 where it curves forwardly over the base 1 and platform 3, there is pivoted thereto a sleeve 7 which is preferably internally threaded and which is provided with a set screw 7a, the pivotal connection of the parts being indicated at 8. Through the sleeve 7 extends a rod which consists of an upper part 6 graduated throughout its entire length and of a lower part 5 carrying at its lower end liquid contact indicators 9 specifically described in Fig. 7. It is obvious that this upper rod part 6 may be fixed within the sleeve 7 by the set screw 7a and this upper part may be graduated or not as desired.

In all of the forms described and shown it will be obvious that the upper part 6 of the rod may be also graduated as indicated in the drawing and that it may be locked in adjusted position by the set screw 7a.

In each of these forms the upper part of the rod as indicated at 6 is connected to the lower part 5 by a pivotal joint 6a, the purpose of which will be presently understood.

Considering the arrangement of Figs. 1, 2 and 3 wherein the sleeve 7 is shown in vertical position, it will be seen that the graduated post 10 permits adjustment of the platform 3 with respect to the base 1 for the reception of the container 4 while at the same time graduations shown on the part 6 may be used to regulate the distance of the contact element 9 above the bottom of the container 4.

However, in the forms shown in the remaining figures a quadrant 13 suitably graduated is fixed to the post 2 so that by tilting the upper section 6 of the rod the lower section 5 may be raised or lowered. The tilting of the upper section of the rod 6 is accomplished by tilting the sleeve 7 and not only can the tilting raise and lower the end 9 but also by moving the upper section 6 through the sleeve 7 a compensating relation may be made between the bottom and the top of the container 4. This is likewise true in regard to Figs. 6 and 8.

For the purpose of indicating accurate contact with the upper surface of the material in the receptacle 4 the member 5 is curved as at 5a and is provided with a lower end 9 which carries lower and upper contact members 15 and 16

which are held, to the member 5 as shown on one side of Fig. 7, by pivots 17.

Now let us consider the operation of the device first in regard to Figs. 1, 2 and 3. The container 4 is placed in the platform 3 and in such position that the lower rod section 5 can reach the bottom thereof. Between this bottom position and the position shown in Fig. 3 the graduations of the upper rod section 6 will appear with relation to the upper edge of the sleeve 7. The graduations 6 may be in any quantity valuation, such as percentages or liquid measures. Also, for instance, the graduations are so arranged that they are in liquid measures and it is desired to fill the container full with definite parts of paint ground in linseed oil and of a dryer such as turpentine. In the first place the rod composed of the elements 6 and 5 is inserted in the container as at Fig. 2 and is raised to measure, by its graduations, the contact 9 to a definite amount of one color of paint such as one-half pint. The container is then filled, in any suitable manner, with the first paint until it measures at points 15 and 16, it being understood that the point 15 will form a meniscus while the point 16 will barely contact with the surface. The container 4, having been filled to this point another quantity of paint such as a pint of a different color is required to be filled therein. The graduated portion 6 of the rod is then lifted until the space between the paint already in the container and that to be filled will amount to one pint. Again, the second paint is supplied to the container 4 until the contact device 9 is reached by the new supply of paint which is then cut off. Supposing the container is one which is intended to contain one quart of paint mixed with turpentine. Then the device is adjusted to the position shown in Fig. 3 and turpentine is supplied until the indicator 9 shows that the container is sufficiently filled. In this manner the quantities, whether the three that have been described or various others, may be regulated. Furthermore, the containers may be of various heights and widths so that by adjusting the platform 3 on the post 2 and securing the same in position as by the set screw 3b this operation may be carried out irrespective of the height of the container.

Regarding such forms as Figs. 4, 5, 6 and 8 it will be observed that the arcuate scales 20 may be used in exactly the same manner as the graduated rod portion 6, the only difference being that the graduated arcs may be used to indicate the vertical movements of the part 9.

What is claimed, is:

1. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, and means indicating the distance of said lower end above the bottom of a container supported on said platform.
- 5 2. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve, a pair of contact members pivoted to the lower end of said rod and adapted to engage the surface of a liquid held in a container on the platform, thereby to indicate the distance of said lower end above the bottom of a container supported on said platform, and means for securing the rod in adjusted position in the sleeve.
- 10 3. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve, a pair of contact members pivoted to the lower end of said rod and adapted to engage the surface of a liquid held in a container on the platform, thereby to indicate the distance of said lower end above the bottom of a container supported on said platform, and means for securing the rod in adjusted position in the sleeve.
- 15 4. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 20 5. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 25 6. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 30 7. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 35 8. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 40 9. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 45 10. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.
- 50 11. In a device for the purpose described, a base, a vertical post fixed to said base, a platform slidably mounted on said post, and constituting a container support, means to secure the platform in vertically adjusted position on the post, said post having its upper end curved to extend over the platform, a sleeve supported by the upper end of said post, a measuring rod movable through said sleeve and having its lower end adapted to engage the surface of a liquid held in a container on the platform, said sleeve being pivoted to the upper end of said post to vary the inclination of the rod thereto and the rod comprising upper and lower pivotally connected sections whereby the lower section is constantly perpendicular, and a dial fixed to said post concentric with said pivot, said dial being graduated to indicate in cooperation with said upper section the elevation of the lower end of said lower rod section above the bottom of a container supported on said platform.

MARIANO VERDUZCO.
